UNITED STATES PATENT OFFICE.

ERASMIUS DARWIN GAINES, OF CLINTON, IOWA.

STYLOGRAPHIC LETTERING INSTRUMENT.

1,271,457.

Specification of Letters Patent.

Patented July 2, 1918.

Application filed September 13, 1917. Serial No. 191,254.

To all whom it may concern:

Be it known that I, ERASMIUS DARWIN GAINES, a citizen of the United States, residing at Clinton, in the county of Clinton 5 and State of Iowa, have invented certain new and useful Improvements in Stylographic Lettering Instruments, of which the following is a specification.

My invention relates to improvements in 10 stylographic lettering instruments and is especially adapted for use in writing or printing on boxes, packages, show cards and the like, and it will be understood that the slight changes in the form or proportion of the various parts that may be necessary to render 15 the invention applicable to its various uses, may be resorted to without departing from the spirit of the invention or sacrificing any of the advantages thereof.

20 My invention relates to that class of lettering instruments having a reservoir adapted to contain a supply of ink or writing fluid, the flow of which is at all times under the control of the operator. Heretofore devices of this class have been unsatisfactory 25 on account of the difficulty of controlling the flow of ink and at the same time providing a flexible writing point or tip which will readily adjust itself to the inequalities of 30 any surface on which it is desired to write.

In my invention I have successfully overcome these objections and it has for its objects, first, to provide a stylographic lettering instrument in which the flow of writing fluid may be controlled by the operator without changing the normal writing position of 35 the instrument in the hand.

Second, to provide a flexible writing tip which may be easily detached for cleaning, 40 and one that will be durable and at all times allow an even flow of writing fluid.

Third, to provide an article that will be cheap to manufacture, easy to assemble, and one that will be easy to clean and keep in 45 order.

Further objects will be apparent through a study of the specification and drawings.

I attain these objects by the means illustrated in the accompanying drawings, in 50 which—

Figure 1, is a perspective view of my invention in position for writing, the finger of the operator being shown in dotted lines and in position to control the flow of writing 55 fluid.

Fig. 2, is a vertical longitudinal section,

the reservoir being shown partially filled with writing fluid.

In the device as illustrated I have shown the reservoir 1 as tapering in form and being largest at the top and provided with an opening 2 for convenience in filling, the opening is closed by means of the cap 3.

While the reservoir may be of any convenient form the tapering form shown is found 65 to be the most practical.

The lower end of the reservoir is provided with an extension 4 forming a passage 5 through which the fluid flows to the tip 6, this extension is also tapering in form.

70 The tip 8 is preferably formed of soft rubber or other flexible material in order to produce a brush like effect, the end being slightly rounded to form a suitable writing point. It will be understood that the point may be 75 broad or narrow as desired to produce the required width of line. The tip is provided with a sleeve 7 having a tapered opening and is adapted to engage the outside of the reservoir extension 4 and thus be held securely in 80 place.

It will be understood that by removing the tip 6 and the cap 3 the reservoir may be very easily cleaned.

75 The tip 6 is provided with restricted openings 9 adapted to carry the writing fluid from the passage 5 to the end of the tip.

The sleeve 7 of the tip 6 is relatively thin at its upper end and thickest at the lower end of the opening 8, this is for the purpose 90 of stiffening and preventing the excessive bending of the tip at the end of the reservoir extension.

An opening 10 is provided in the top of the reservoir for the purpose of allowing 95 air to enter as the writing fluid is used, and a flexible valve 11 is secured to the reservoir by means of the rivet 12 and is adapted to close the opening 10 when the instrument is laid flat or is inverted, but is so arranged 100 as to allow the entrance of air when in position for writing.

A passage 13 extends from the opening 10 down the side of the reservoir and to a point near its lower end, this passage is then 105 turned outwardly and provided with a flange 14 adapted to receive a rubber 15, the bulb is provided with a hole 16 to receive the flange 14 and thus be held securely in operative position. A small opening is provided in the bulb as shown at 17 and is 110 adapted to be closed by the finger of the

operator when desired to prevent the too rapid flow of writing fluid.

The bulb 15 is located near the tip and in a convenient position to be operated by the finger when the instrument is held in the normal writing position.

When it is desired to increase the flow the bulb is pressed the desired amount thus increasing the pressure of air in the reservoir and causing the writing fluid to flow more rapidly through the tip. In writing on rough boards or boxes the holes in the tip may become clogged with dirt or dust and in that case a quick pressure of the finger on the bulb forces the fluid through the openings in the tip thereby providing a means for effectually cleaning the instrument without unnecessary delay.

It will be understood that my invention may be varied in its physical embodiment without departing from the scope of the invention and the specific form and construction herein shown is to be taken in an illustrative and not in a limited sense.

Having thus described my invention what I claim is:

1. In a writing instrument the combination with a conical ink reservoir provided with a flexible writing tip, of an air inlet passage tube secured along the wall of the reservoir and opening at one end into the base end of said reservoir, the other end of said tube terminating at a point near the

apex of said reservoir, said passage being provided near the base of the reservoir with a valve adapted to prevent ink from entering the passage. 35

2. In a writing instrument the combination with an ink reservoir provided with a writing tip, of an air passage tube secured along the side wall of the reservoir and opening into the base end of said reservoir, one end of said passage terminating near the apex of said reservoir and being provided with an outwardly extending flange, a flexible bulb having an opening adapted to receive said flange and a second opening adapted to be closed by the finger of the operator. 40 45

3. In a lettering instrument the combination with an ink reservoir, of a flexible writing tip on said reservoir, said tip being provided with openings for the passage of ink, an air passage tube secured along the side wall of said reservoir and opening into the base end of the reservoir, a valve secured to the inside of said reservoir and adapted to allow air to enter the reservoir and prevent ink entering the passage, said air passage extending to a point near the tip and provided with an outwardly extending flange, a flexible bulb provided with an opening adapted to engage said flange and a second opening adapted to be closed by the finger of the operator. 50 55 60

E. DARWIN GAINES.
